Application February 2, 1939, Serial No. 254,174

28 Claims. (Cl. 141—1)

The method and apparatus of my present invention relate to and are appropriate for the washing and sterilizing of any articles and goods adapted for immersion in water, including such things as glassware, food receptacles and utensils, especially those used in hospitals, hotels and restaurants, in fact any immersible articles as to which cleanliness and sterility are important or desirable. One of the most important applications of the invention is in connection with surgical practice, for post-operative cleaning and sterilizing of instruments and other surgical equipment. In its broad aspects, however, a main object of the invention is to provide a new method and means for rapidly, safely and certainly cleaning and sterilizing any articles for which such treatment is in order and as to which a brief immersion in superheated water is not objectionable.

In the drawings illustrating by way of example certain embodiments of the invention and means for practicing the method thereof,

Fig. 1 is a view mainly in vertical section of one form of washing sterilizer;

Fig. 2 is an enlarged horizontal section through the sterilizer, just below the cover;

Fig. 3 is a detail section on the line 3—3 of Fig. 2;

Fig. 4 is a view corresponding to Fig. 1 illustrating a further embodiment;

Fig. 5 is a view corresponding to Fig. 1 illustrating a further embodiment, particularly suitable for the treatment of larger or more numerous articles;

Figs. 6, 7 and 8 respectively are a section, an elevation and top plan of a flash tank comprised in the apparatus; and

Fig. 9 is a chart explanatory of the cleaning and sterilizing cycle, in a surgical operating room.

The common practice in sterilizing surgical instruments for the operating table does not insure absolute sterility. Bacteriologists have repeatedly pointed out that boiling water does not kill spores even after prolonged exposure. Abbreviated boiling periods, the use of oil on instruments, the formation of scale in hard water areas, and depressed boiling temperature caused by altitude are additional factors causing inadequate sterilization. The safety of a technique based upon boiling depends upon the care with which spore-bearing organisms and spores have been excluded by mechanical means. Inevitable disaster results whenever dangerous spores are not removed from instruments prior to sterilization

by boiling. In short, there have heretofore been no absolutely reliable methods for the post-operative sterilization of instruments contaminated with oil, feces, blood, or pus known to contain virulent bacteria or spores.

Nevertheless, the disinfection of instruments from septic cases or instruments soiled by pus or feces where spore bearers are likely to be encountered, has received much attention. The danger of spore-bearing organisms in the operating room has been recognized and special techniques for the routine sterilization of such instruments have been devised. The number of techniques in use and the wide range of minimum standards for sterilization of these instruments are indications of the inefficiency of the existing methods of caring for "dirty" instruments. The only safe bacteriologic technique of those in current use is that of immersing the soiled instruments in a 10 per cent soap solution and autoclaving them at 250 degrees F. for 30 minutes. This practice has the disadvantage of using equipment primarily designed for another purpose. The interior of the autoclave is usually fouled with soap and denatured proteins which are spattered on the chamber wall when the steam is vented. The danger of scalding the attendants who remove the instruments from the sterilizer is great. Soaking dirty instruments in a germicide, prolonged boiling after thorough scouring and scrubbing, or combining these in various ways is not only time-consuming but also removes the instruments from circulation. What is of greater importance to safety, dangerous spores may be spread throughout the operating room during the cleansing process, or sterilizers may be contaminated with spores which survive hours of boiling.

My present invention provides a safe, rapid technique for the cleansing and sterilization of such instruments and other articles, by exposing them to heated water, carrying the oil and other insoluble matter to the surface of the water, and removing the oil and scum from the water surface, leaving thereon at the most a monomolecular film of oil, which can be sterilized.

Referring now to the drawings, in Figs. 1 to 3 I have illustrated one embodiment of apparatus for the practice of my method. As there shown, the shell or main receptacle 6 of the autoclave or washing sterilizer is set in upright position on a stand or base 7. The main chamber 8 is thus vertically disposed, that is, arranged for opening at the top, where a pressure-tight closure or cover 9 is provided. The latter may be of any

preferred form, that shown being carried on a diametral cross arm 10 having one end pivoted on the top ring or casting 11 and its other end arranged to interlock with a hold-down at an opposite point on said ring. A pivot post 12 rising centrally from the cover is threaded through the cross arm 10 and provided with a turning bar or handle 13 for clamping the cover securely in closed position. The autoclave as a whole including the parts described is constructed to withstand an operating pressure of 27 pounds per square inch (gauge pressure) with adequate safety factor.

Heating means is provided in the chamber 8, adjacent its bottom, in this instance in the form of a steam coil 15. One end of the coil communicates through the sterilizer shell 6 with a steam supply pipe 16 and the other end is connected with a steam outlet conduit 17 leading through a trap 18 to the steam return line 19. The steam coil is of large capacity, for quick-heating effects, and is so designed and positioned as to concentrate the greatest heat at the side of the sterilizer opposite the overflow to be referred to. Thus in Fig. 1, the overflow being at the rear, said heat concentration is at the front, at which location the inlet end of the coil is installed.

The steam coil 15 is enclosed by a baffle 20 herein including a supporting base 21, a perforate plate 22 overlying the coil and an upwardly extending flange 23 adapted to support the article receptacle or bucket 25 and to force the water in the sterilizer to circulate upwardly through the perforate article-receiving shelf 26, herein at the bottom of the bucket.

The dirty instruments or other articles A to be washed and sterilized are collected on the perforate floor of the bucket 25, directly from the operating table or other point of contaminating use. The bucket preferably is of stainless steel, Monel metal or other non-corrosive material, and is of a size to be easily receivable in the sterilizer, in spaced relation to the side walls, and to extend well up toward the top of the chamber 8. A depending peripheral flange 27 at the bottom of the bucket serves to position the latter on the top flange 23 of the baffle. After the bucket 25 containing the articles A is set into the sterilizer the latter is filled with water until it overflows at the knife-edge overflow to be described. The water is admitted, and subsequently drained, at the bottom of the sterilizer shell through a relatively large port 28, for quick filling and emptying, the port desirably being screened as at 29. Communicating with the chamber port 28 is a 3-way valve 30.

One port of this valve 30 is connected with a conduit 31 leading to the water supply, at any convenient point adjacent the sterilizer, above it in the illustrated example. Interposing said conduit 31 and the water supply line is a water supply valve 32 and an air break device 33. The latter insures that the liquid in the sterilizer can never return into the water supply system under a siphoning or other action, such as might otherwise occur for example in the event of a drop in the pressure of the water supply. Another port of the 3-way valve 30 is connected with an emptying pipe 35 leading to a flash tank mounted at the rear of the sterilizer or other convenient point, adjacent or remote, for example, in the basement of the building.

The flash tank referred to is a device whereby the heated water under pressure can be suddenly

released to atmospheric pressure, in a safe, quieted manner. Such device, as adapted to be mounted on or adjacent the sterilizer or otherwise incorporated in the apparatus as a whole, is illustrated by way of example in Figs. 6 to 8. As there shown, upon a somewhat smaller scale than Fig. 1, it comprises a closed tank 43 having a capacity at least one-third that of the sterilizer chamber. The pipe 35 from the sterilizer enters the tank 43 at a relatively low point and discharges into the tank, preferably adjacent a side wall, as seen in plan in Fig. 8. The wall of the tank opposite the pipe 35 desirably is shaped to have a deflecting, and hence silencing, action on the incoming stream of water, as seen in said Fig. 8. The energy stored in the water is dissipated by vaporizing a portion of it, which is carried from the tank by means of a vent 44 of relatively large size, desirably at least twice the diameter of the inlet pipe 35. The residual water accumulates at the lower portion of the tank and is drained to waste through a deep sealed trap 45 having its mouth near the bottom of the tank and communicating outwardly and through an air break 46 to the waste drain. A series of baffles or vanes 47 may be installed in the tank to assist in silencing the action and cooperating in distributing the water around the specially shaped tank as described.

Referring again to Fig. 1, the filling, closing and draining valve 30 of the sterilizer may be of the plug type or other suitable form constructed and arranged to afford the desired three positions. In one position of the valve, water is admitted to the sterilizer chamber 8 at its port 28 through the conduit 31 leading from the water supply, the emptying port of the valve being closed in this position. In a second position the chamber port 28 is completely closed off, both from the water supply and from the emptying line. In the third position of the valve the water port is closed and the sterilizer chamber is placed in communication through the outlet 28 with the emptying line 35. The valve operating stem 36 is extended to a conveniently accessible point, herein at the front of the sterilizer, where it is provided with an operating handle 37 desirably having a pointer 38 movable over a dial 39 marked with suitable indicia such as Fill, Sterilize, Drain, corresponding to the valve settings as above described.

The water may be admitted to the chamber 8 either before or after closing the latter. Preferably the cover 9 is closed and secured before turning on the water, the filling of the chamber up to the desired level, that of the overflow 50, being indicated by water flowing from the ejector 53, as is visible and audible at the air break 51 (these elements to be described shortly). Thereupon the water is shut off and the valve 30 turned to the sterilizing position.

The sterilizer thus closed and its chamber 8 filled with water to the indicated level is in readiness for the washing and sterilizing of the articles in the submerged container or bucket 25. Heat is then supplied in the chamber, herein below said bucket 25, in this instance by the admission of steam to the large-capacity coil 15, effected by opening a valve 49 placed in the steam supply line at a convenient point adjacent the sterilizer. This valve 49 may be manually operable, both as to opening and closing but desirably and as shown in Fig. 1 it is constructed and arranged for manual opening, and automatic closing upon attainment of the desired pressure

and temperature in the sterilizer. In the illustrated example of Fig. 1 this steam valve has a manual plunger 41 adapted to be pushed down to open the valve, through a toggle connection which crosses center and acts to hold the valve in open position, subject to automatic closing under the action of a diaphragm one side of which is in communication with the interior of the sterilizer, as through the valve-closing line 42. Or the automatic closing of this steam valve may be effected electrically as by a solenoid in series with the thermostatic switch 68 later referred to.

With the flow of steam through the coil 15 the water is rapidly heated and convection currents are set up in it, as indicated by the arrows in Fig. 1. These cause the oil, grease, or other insoluble dirtying matter leaving the instruments in the bucket to rise to the surface of the water as a scum. This then continuously moves toward the overflow or discharge port 59 at one circumferential portion of the water chamber 8, herein at the rear of the sterilizer. The upward inclination of the baffle plate 22, together with the fact that the steam coil is arranged so that the steam is introduced at the side of the sterilizer opposite the overflow, assists in this movement of the water and in directing the surface flow toward the discharge or overflow port 59.

The novel construction and arrangement of this overflow or discharge port will best be understood by reference to Figs. 2 and 3. In this embodiment it comprises a horizontally disposed aperture 59 at an upper side wall of the chamber, herein in the top ring or casting 11. The lower boundary of this port has a formation 51 which I herein refer to as a knife-edge or free-overflow.

By these terms I intend a wall, edge or dam having a relatively narrow top face or edge, of such restricted cross-dimension, in the direction of the flow, and also of such extent circumferentially of the chamber, that the holding back of any scum, foam or the like upon the surface of the water at the overflow 51, behind said formation, is reduced to the practical minimum.

Under the theoretical ideal this knife-edge 51 would be substantially a line but the inherent limitations of available materials and other practical considerations generally prescribe some appreciable thickness of material at the edge. In actual practice it is found that this thin-edged dam 51 should not greatly exceed in width about one eighth of an inch, while the reduction of the edge thickness to about one thirty-second or one sixty-fourth of an inch or even less affords additional surety of efficient operation. Circumferentially, it is found that by extending this free-overflow formation 51 over a substantial fraction of the total circumference or periphery of the water chamber any damming or scum-forming effect is substantially completely avoided, there being no obstruction behind which the scum can back up. The preferred extent is found to be one approaching one third of the circumference of a circular chamber such as that of Fig. 1 but good results have been obtained with less extensive overflows, particularly where the water chamber is rectangular or other polygonal shape in horizontal section, as for example in the embodiment of Fig. 5. In the latter case the overflow extends across one straight side of the chamber. The main consideration in this connection is that there shall

be no angle, corner or pocket-like formation at the longitudinal ends of the overflow formation 51 behind which any appreciable scum or floating matter may be retarded or trapped.

From the described knife-edge 51 defining the line of overflow, the lower wall of the overflow or discharge port 59 is sloped away sharply, desirably at an angle of at least about 45 degrees to the horizontal, as best seen in the enlarged detail section of Fig. 3, at 52. This wall merges outwardly and downwardly into a collecting basin 53 the floor of which slopes directively, in the manner of a funnel, toward an exit 54 at its lowermost portion.

Said exit port 54 has closed connection with a discharge reservoir 55, another element importantly contributing to the effective carrying off of the discharge from the washing and sterilizing water chamber. This reservoir, in this example in the nature of a stack outside the chamber 8, is connected at or near its bottom with an ejector 56 discharging through an air break 57 to a conduit 58 leading to the available drain.

The ejector or pressure-retaining discharger 56 is constructed as a sensitive thermostatic steam trap of large capacity, adapted to be actuated intermittently with ejecting effect in response to comparatively small temperature differentials. In cooperation with this ejector the discharge reservoir, whether external as in the case of the element 55 of Fig. 1, or internal or partly internal as in Figs. 4 and 5, is proportioned and arranged, with substantial volume content, to provide for the storage of a quantity of overflow while the latter cools sufficiently to cause the ejector 56 to function. This temperature differential, made possible by the provision of the discharge reservoir, effects the intermittent ejecting action of the thermostatic ejector 56, without causing the overflow to be choked by hot fluid dammed behind a closed ejector.

The sterilizer desirably is equipped with a pressure gauge 60 located at any convenient point and in communication with the interior of the chamber 8, being illustrated in Fig. 1 as let into the casing 11 adjacent the discharge port 50. A safety valve 61 may conveniently be installed in communication with the coupling 62 for the gauge. The safety valve coupling may also be used for connecting the pressure line 42 for closing the automatic steam shut-off valve 40 previously described. Any other customary or desired safety features may be incorporated, such for example as a bleeder valve and discharge line from the water supply valve 32 to the drain, as shown in the case of Fig. 4, to carry off any possible seepage from the water supply at said valve, which conceivably might reach the chamber 8 and contaminate the sterile contents.

With the admission of steam to the coil 15 the water in the chamber 8 is rapidly heated. Convection currents as previously referred to are set up and there results also a continual rise in the water level, due to the expansion of the heating water. Accordingly the oils and insoluble dirty matter formed by the blood and pus rise to the surface of the water and are carried over the knife-edge overflow 51 by the constantly rising water, into the discharge reservoir 55 whence they are ejected into the drain by the ejector means described.

The movement of the oily dirty matter at the surface of the water and across the overflow is also in substantial part due to the inherent property of such oily masses to endeavor to spread

over a limitless surface of water, which effort is maintained until but a monomolecular expanded film remains. The non-obstructing knife-edge overflow provides, in effect, a limitless surface at the overflow level of the water chamber, and permits this expanding property of the oily material to be availed of in the functioning of the apparatus. The final remaining monomolecular film, if any, is itself readily sterilized and is too slight to dirty the instruments as the water is subsequently drained from the sterilizer.

From the foregoing description in connection with the drawings, it is evident that any body of air in the closed chamber, after admission of the water, whether the latter is admitted before or after closing of the chamber, is in the space above the water level; where the water is let in after closing, a volume of air equal to that previously in the water-occupied portion of the chamber passes out through the fluid overflow and discharge port 50. During a first part of the heating operation, any air till then remaining in the space above the water, and which is relatively cool, passes off and down to and through the ejector 56 with the liquid and ahead of the steam forming in the closed chamber, it being noted that the port 50 is at the liquid level, the lowest point above the liquid in the chamber.

The addition of a detergent, to peptonize the proteins and saponify and peptize the greases, removes all the dirt, eliminating the necessity for mechanical cleansing of the instruments. The use of sodium hexametaphosphate or similar material, such as that known commercially as "Calgonite," in the detergent softens the water and prevents the precipitation of a film of alkaline earth, soaps and salts on the instruments.

The described heating and discharging action is rapidly carried on through a cleaning period which may be considered as lasting until the water has been heated to approximately 250 degrees F. From that point the action is continued uninterruptedly for a period affording a large factor of safety and assured sterilizing effect upon the articles in the bucket, until a temperature of 270 to 273 degrees F. is attained, with the corresponding gauge pressure of 27 plus to 29 plus pounds per square inch. Under the automatic operation described in connection with the pressure-closing valve 40 of Fig. 1, the steam supply is thereupon automatically shut off. Desirably also a signal is given to the attendant, automatically, to notify that the steam supply has been shut off, or indicating that it is proper to do so in the case of a manually operated steam control valve, such as shown for example in Fig. 4.

Such signal may be visual or audible. In Fig. 1, I have shown for the purpose a signal light 65 located at some readily observable point, as adjacent the dial 39 previously referred to, at the front of the sterilizer. Power for the signal light may be provided by a plug-in connection 66 with the supply main, the light being connected in series, through a conductor 67, with a thermostatic switch 68 subject to the temperature conditions in the sterilizer, for example, in the discharge reservoir 55, as illustrated. This switch is regulated for actuation at the selected temperature adequate to insure sterility, including the killing even of resistant spores, for which purpose I prefer to use 273 degrees F.

On receipt of the signal the attendant manipulates the valve handle 37 to turn the 3-way valve 30 to "drain" position. The heated water

rapidly drains off from the chamber 8 through the pipe 35 and into the flash tank 43 as previously described. Following this emptying of the water contents the instruments or other articles 5 in the bucket become subject to the remaining saturated steam in the sterilizer while the pressure is being relieved. After the steam passes off and the sterilizer is opened, the residual heat in the instruments is sufficient to flash any adherent moisture.

Thereupon the clean, dry, sterile instruments or other articles are ready for immediate use upon removal from the sterilizer. The action of this sterilizer is so rapid and satisfactory that it 15 may be used for the routine sterilization of surgical instruments, thereby supplanting less efficient methods. Various other uses for this cleaning and sterilizing apparatus, in hospitals and other institutions, hotels and elsewhere, will 20 be evident.

The described operation of the pressure washer-sterilizer apparatus of my invention will 25 readily be understood and visualized from an inspection of the chart, Fig. 9. This chart shows graphically the actual operation and results obtained in a surgical operating room with a typical sterilizer embodying the invention, such as that of Figs. 1 to 3. The time-temperature curve is plotted in units of operating time 30 against degrees of temperature Fahrenheit. A key explanatory of the marked areas of the chart is found at the lower right corner portion of said Fig. 9. As there seen, a black area of the width indicated represents a 10-second unit of the 35 nurse's or attendant's time. Like time units of heat required to kill resistant spores, and factor of safety time units are indicated respectively by the slanting lined area and the dotted areas.

The charted operation commences at the zero 40 point with the collecting of the dirty instruments from the operating table, represented as occupying about 15 seconds of the nurse's time. Within the next 2 minutes the loaded bucket 25 is placed in the sterilizing chamber, 45 the cover closed and secured and the sterilizer filled with water. At a time point shortly beyond the 2-minute line of the chart the steam supply is turned on and the heating commences. The temperature rises rapidly following a regular curve closely approaching a straight line, 50 continuously to the 273 degrees F. point, reached in this case in approximately 3 minutes from the time when the steam is admitted. The cleaning period, with substantial safety factor, 55 is indicated by the bracket, being completed in this instance at the end of 5 minutes from the zero time point at which the collecting of the instruments was started. The time of absolute sterilizing temperature at 273 degrees F. arrives about one-half minute later, is indicated by the signal, and the steam is shut off, automatically or otherwise. The nurse or attendant, noting the signal, turns the valve 33 to emptying position. The temperature and pressure are maintained in the sterilizer for approximately 1 minute 65 while the water is drained into the flash tank. An abrupt temperature drop occurs following the draining of the sterilizer and complete relief of pressure. After the indicated drying period of approximately 10 seconds the 70 contents of the bucket are completely sterile and dried and in full readiness for use for their intended operating or other purposes, the entire cycle occupying substantially under 10 minutes and in this case actually less than 8 minutes, in-

cluding a total of but about 3 minutes of the attendant nurse's time.

In Fig. 4 I have illustrated another washer-sterilizer embodying my invention and by which the method thereof may be practiced. In this example similar reference numerals indicate corresponding parts as in the previous figures. Parts not otherwise referred to may be assumed to be the same as in said earlier figures. The apparatus of Fig. 4 is more particularly intended for installations where the available budget necessitates a relatively inexpensive structure for the sterilizer as a whole and where such features as automatic control or extremely rapid operation are less important.

Referring to Fig. 4, the steam supply line 16, controlled by a manual valve 40a, leads directly into the main chamber 8 of the sterilizer, as at 16a. Within the outer or main shell 6 there is installed an inner container 70 of general bucket form, having a closed bottom 71 and a circumferentially continuous side wall 72 the top edge 73 of which is spaced below the cover of the sterilizer.

This container 70 in this example provides the water chamber in the sterilizer, whereas in the case of Figs. 1 to 3 the water is admitted directly to the main or outer chamber 8 as the water chamber. The discharging overflow of the water, in Fig. 4, takes place across the top edge 30 of said inner container or water chamber 70. Said edge accordingly is formed in such manner as to provide a knife-edge or free-overflow formation within the definition of those terms as given in connection with Figs. 1 to 3, said formation extending through a substantial arc, desirably at least about one fourth to one third of the circumference. As illustrated said overflow formation extends completely around the top of the chamber 70.

This water container or chamber 70 is supported within and in spaced relation to the main outer shell 6. The space between them, at the sides and below the chamber 70 together with the discharge conduit 77 provides a discharge reservoir corresponding functionally to the element 55 of Figs. 1 to 3. A water inlet-outlet port 74 in the bottom wall 71 of the chamber 70 is connected with the 3-way valve 30 by a short pipe 75 extending through the base of the outer shell 6. As in the previous example, one port of the 3-way valve 30 is connected by a conduit 31 and through an air break 33 to the water supply line, controlled by a water supply valve 32.

The principle of operation is essentially the same as fully explained in connection with Figs. 1 to 3 and the chart of Fig. 9. The instruments or other articles to be cleaned and sterilized are collected in a bucket or basket 25 having not only a perforate bottom 26 but also perforate side walls 26a. This bucket is adapted to be received in the water chamber 70, in spaced relation to the latter, with its top edge ending distinctly below the overflow knife-edge 73 of said chamber.

Similarly as in the previous example, the instrument bucket and the container or water chamber 70 are filled with water, by turning the 3-way valve 30 to the appropriate position, until the level of the water reaches the knife-edge overflow 73. The water supply is then shut off and the 3-way valve 30 turned to operating position, closing off the inlet-outlet port 74 completely. The sterilizer being closed and secured, the steam is admitted by manipulation of the steam valve 40a.

The steam thus admitted throughout the main chamber 8 acts to heat the water in the chamber 70 and bucket 25, setting up convection currents and also causing the constant overflow of the water at the knife-edge 73 due to its expansion as it becomes heated. The expansively spreading and overflowing dirty oily material and water passes down outside the water chamber 70, between the latter and the main shell 6, to a discharge port 76 at the bottom of the latter. A discharge conduit 77 leads from this port to an ejector 56 discharging through an air break 57 to a drain connection 58 similarly as in the previous example. As previously stated, said discharge conduit 77 and the space at the sides and bottom of the main sterilizer chamber 8, between the walls of the latter and the water chamber 70 constitute a discharge reservoir within which the fluid is cooled sufficiently to operate the ejector 56. The thermostatic switch 68 for controlling the signal 65 may be located at any appropriate point subject to the sterilizing temperature conditions, as in the discharge conduit 77, ahead of the ejector 56. A pressure gauge 60 and safety valve 61 may be provided, in communication with the main sterilizer chamber 8 through a passage 60a in the top ring or casting 11. A bleeder connection and carry-off line for the water supply valve 32, mentioned in connection with the previous figures, is illustrated at 78.

In Fig. 5 I have illustrated a further embodiment of the invention. The sterilizer in this instance is horizontally disposed, being particularly adapted for the cleansing and sterilization of bulky objects loads of dishes, and other loads more readily presented and removed horizontally. These may be inserted into the sterilizer on a small truck or rack, or other open support on which they may be immersed in and subject to the action of the water, as in a perforate receptacle or basket as in the previous figures. The horizontal form of sterilizer of Fig. 5 may equally be used for any of the purposes of those of Figs. 1 and 4.

Like reference numerals indicate similar elements in Fig. 5 as in the preceding figures, and parts not otherwise mentioned may be assumed to be the same. The main enclosure 80 may be of any usual or preferred general construction for a horizontal autoclave or sterilizer, including a closure 81, the whole adapted to withstand pressures of 27 pounds with adequate safety factor. The article support 82, illustrated as a perforate or open-mesh shelf or tray is inserted and positioned at the lower portion of the sterilizer chamber 83, and spaced inwardly from the front closure, as upon tracks or ways (not shown).

This article-receiving portion of the main chamber 83 is adapted to be closed off at the front, to constitute the water chamber or compartment 84, by means of a displaceable partition or bulkhead 85. This partition is constructed and arranged so that it may be moved out of the path of the articles and their support, in inserting and removing them, but may be fastened in place to form a watertight dam across the lower front portion of the sterilizer chamber 83 and defining the front wall of the water chamber 84. For this purpose the partition may be pivotally mounted in the sterilizer as indicated at 85a, or otherwise movably positioned therein, or disposed for bodily removal from positioning guides on the chamber wall. The upper edge of this dam or partition 85 is formed to provide the knife-edge

or free-overflow formation 86 as previously described.

The steam coil 15 is located in this case at the rear of the water chamber 84, opposite the overflow 86 and beneath a perforate baffle 20 inclining upwardly and rearwardly, to aid in directing the water currents, indicated by the arrows, in the same general manner as in Fig. 1. The steam supply pipe and control valve are indicated at 16 and 40a respectively, the water inlet-outlet at 28, the 3-way valve at 30, the water supply line at 31 and the drain line at 35 leading to the flash tank 43, all generally similar as in the previous figures.

The overflow across the knife-edge 86 runs into the compartment 87 at the front of the sterilizer and through the discharge port 88 and discharge conduit 77 to the ejector 53, from which it is ejected past the air brake 57 to the drain conduit 58. It will be seen that said compartment 87 and the discharge conduit 77 provide a reservoir for the overflow, for cooling it to afford the ejecting action, similarly as in the previous examples. An automatic signal of the arrival of sterilizing temperature, and automatic cut-off of the steam supply may be provided if desired, as in the other embodiments. In the example of Fig. 5 the water compartment within which the articles are supported in immersed position is provided in part by the wall of the sterilizer chamber and in part by the movable bulkhead 85, while in Fig. 1 the overflow is in effect built into a wall of the sterilizer chamber which itself is also the water compartment, and in Fig. 4 the water compartment is in a container spaced from the main chamber walls. In other instances the water compartment may be a unit which is bodily removable relative to the main enclosure of the sterilizer.

From the foregoing it will be apparent that the method of my invention includes some or all of the following steps or operations: subjecting dirty articles and instruments to be cleaned and sterilized to immersion in water in a pressure-tight main chamber, applying heat to and raising the temperature of the water to a heated state; carrying off from the articles any dirty oily matter thereon, raising it to the surface of the water and causing said matter to be continuously discharged from the water chamber and from the sterilizer until substantially but a monomolecular oil film remains on the water surface, sterilizing said film, continuing the heating action until a selected temperature preferably of at least 270 degrees F. and a corresponding steam pressure are reached, signaling the arrival of said temperature, cutting off the heat supply manually or automatically, draining the water chamber and relieving the pressure in the sterilizer, and effecting the complete sterilization and drying of the treated articles in the sterilizer, in full readiness for use.

My invention is not limited to the particular means or steps as herein illustrated or described, and I point out its scope in my following claims.

I claim:

1. Washing and sterilizing apparatus comprising, in combination, a pressure-tight main enclosure having a water-receiving chamber therein, perforate means for supporting articles at an intermediate level in the chamber so as to subject them to vertical currents in the water therein, means to heat the water, overflow lip means on a wall of the chamber above the supported articles, said overflow means having a crest defining the maximum water level and there providing

uninterruptedly over a substantial horizontal extent a free escape for heated water expansively rising above said level, a reservoir for the fluid from such overflow means, and pressure-retaining means to discharge the fluid from the reservoir while maintaining the temperature and pressure in the main enclosure and its water chamber.

2. A pressure washer-sterilizer comprising in combination, a main pressure-tight receptacle having a closure affording access for objects to be washed and sterilized, a water chamber in said receptacle having a vertical wall thereof provided with an upright free overflow formation of an uninterrupted horizontal extent defining the highest water level and in effect there providing for the water a limitless surface area for the expansion of water-carried matter rising to said surface, means whereby the objects to be treated are positioned in the water chamber below said overflow formation and in the path of upward currents in the water therein, heating means for the water in said chamber, and discharge means to carry off the overflowing liquid while maintaining the chamber temperature and pressure.

3. A pressure washer-sterilizer comprising, in combination, a main pressure-tight enclosure having provision for loading, a load-receiving water chamber therein, means to heat the water in said chamber to steam-producing condition, said enclosure serving to confine the evolving steam, a pressure-maintaining discharge outlet from the enclosure, horizontally extensive overflow means for the water chamber presenting a knife-edge formation defining the water level and over which the surface water and matter carried by it may flow freely from the chamber to the discharge outlet, and means in the water chamber below the knife-edge formation whereby the load to be washed and sterilized is held in immersed suspension in the heated water in said chamber.

4. Sterilizing apparatus comprising, in combination, a pressure-tight enclosing chamber including a water-receiving portion, an inner open-top container for a load to be treated, means positioning the container in said water-receiving portion of the chamber, an overflow edge formation of substantial horizontal extent disposed at a lateral boundary of the water-receiving chamber portion and defining the upper water level therefor, means to heat the water to temperatures above the normal atmospheric boiling point and under pressure developing in the chamber while permitting it to overflow at said edge formation, and means to receive and periodically discharge the overflow.

5. Sterilizing apparatus comprising, in combination, a pressure-tight enclosing chamber including a water-receiving portion, upwardly open means in the water-receiving chamber portion to position the load to be sterilized, an upstanding edge formation at a lateral wall of the water-receiving chamber portion, said formation spaced below the chamber top wall and above the load position to define the upper level of the water, heating means to heat the water to temperatures above the normal atmospheric boiling point and under pressure developing in the chamber, and thermally responsive receiving and discharging means for the overflow from said edge formation.

6. Sterilizing apparatus comprising, in combination, a sterilizing chamber adapted for pressure-tight closure, an inner open-top container for the load to be sterilized, means positioning the container in spaced relation to the bottom

wall of the chamber, said chamber with the container therein adapted to receive water to a determined level above the container and below the chamber top wall, a horizontal overflow formation of substantial extent disposed on a wall laterally of the container, above the top of the load therein and determining the upper level of the water, means for producing a steam-pressure-subject heated condition of the water under which it overflows said formation, and receiving and pressure-retaining discharge means for the fluid in communication with said overflow formation.

7. Sterilizing apparatus comprising, in combination, a water and steam receiving chamber adapted for pressure-tight closure, an inner open-top container for a load to be sterilized, means positioning the container to support the load above the bottom wall of the chamber and below a determined water-level therein, said container having a lower wall providing for upward passage of water through it, a fluid-escape wall formation on a wall in the chamber having a horizontal upper edge above the top of the container and defining the water level in the chamber, heating means for the water, and means to receive and to discharge from the chamber the fluid which overpasses said edge of the wall formation.

8. Sterilizing apparatus comprising, in combination, a closure-equipped sterilizing chamber constructed and arranged to receive a load for sterilizing and to enclose a body of water submerging the load, said chamber provided with a substantially vertical wall confining the water laterally, said wall having an upstanding horizontally extending edge formation in spaced relation to the chamber top wall and adapted to define the water level above the submerged load, heating means for the water, and thermally responsive pressure-retaining means associated with the chamber to receive and discharge water overflowing said edge formation.

9. The method of washing and sterilizing contaminated loads which comprises pressure-tightly confining a body of water while providing a limited enclosed space above the water level, submergently positioning the load in the water, heating the water and inducing convection currents therein aiding to carry oily matter from the load to the water surface, affording free lateral egression for the rising heated water substantially at its surface level and thereby enabling the surface-carried oily matter to expand as over a limitless area so that any such matter finally remaining is reduced to substantially a monomolecular expanded and ready sterilizable film at the water surface, and passing off the fluid so egressing while maintaining a heated condition of and pressure upon the water retained.

10. The method according to claim 9 including the steps of subsequently releasing and carrying off the residual water and relieving the pressure within the remaining load-enclosing space.

11. The method according to claim 9 including the steps of discontinuing the application of heat following arrival of a selected above-normal-boiling temperature, subsequently releasing and carrying off the residual water, exposing the load to saturated steam and relieving the pressure within the enclosed load-containing space.

12. The method according to claim 9 including the steps of discontinuing the application of heat

following arrival of a selected above-normal-boiling temperature, subsequently releasing and carrying off the residual water, exposing the load to saturated steam, relieving the pressure within the enclosed load-containing space and utilizing in the practice of said method temperatures such that the residual heat in the load when including articles such as surgical instruments, following said relieving of the pressure, is sufficient to flash adherent moisture, whereby the clean, dry, sterile instruments are ready for immediate use.

13. In a sterilizer, in combination, a pressure-tight enclosure, a water compartment in said enclosure, means to heat the water therein, said compartment having laterally thereof a free overflow formation below the top wall of the enclosure and determining the maximum water level for the compartment, said formation comprising an upright wall having a thin knife-like upper edge and of such contour and extent peripherally of the water compartment as to present the minimum obstruction of surface-carried matter at said formation and pressure-retaining outlet means for releasing said overflow from the enclosure.

14. In a sterilizer, in combination, a pressure-tight enclosure, a water compartment in said enclosure, and means to heat the water therein, said compartment having laterally thereof a free overflow formation of substantial horizontal extent, said formation disposed below the top wall of the enclosure and determining the maximum water level for the compartment, a reservoir in communication with and adapted to receive the liquid overflow from said formation, and thermally responsive pressure-retaining discharge means associated with the reservoir, the latter and the water compartment being of such relative volume and arrangement as to provide for a collecting of the received fluid and resulting intermittent actuation of the discharge means whereby a continuous overflow and carrying off of the fluid is afforded under avoidance of any return backing-up of fluid to the enclosure.

15. A washer-sterilizer comprising in combination a vertically disposed outer shell having a top closure; a like-disposed water chamber in the shell, valve-controlled means to admit water to and drain it from said chamber, a free-overflow formation at an upper portion of the chamber, a valve-controlled steam coil at the lower portion of the chamber to heat the water therein, supporting means for the articles to be treated, said means disposed below the overflow formation and arranged to position the articles in the water above the steam coil and in the path of water currents set up by the heat therefrom, a reservoir to receive the rising heated fluid passing said free-overflow formation, and ejector means to discharge said fluid from the reservoir.

16. A washer-sterilizer comprising in combination an outer shell having a closure for admission and removal of articles to be treated, a container in said shell, spaced from its walls and providing a water chamber, means to admit water to and to drain it from said chamber, heating and vertical current producing means for the water, supporting means for articles in the water chamber to hold them in immersed position subject to upward currents in the water, valve-controlled means to supply steam in the shell to heat the water in said chamber, a horizontally extensive free-overflow formation upon a wall of the water chamber above the supported articles, and a conduit and ejector means commun-

cating with a lower portion of the interior of the shell for receiving and discharging the fluid coming from said overflow formation.

17. Washer-sterilizer apparatus comprising in combination a horizontally disposed autoclave having a pressure-tight door at its front end, article supporting means at an intermediate level in the autoclave and spaced rearwardly from the door, a vertical watertight partition extending laterally in the autoclave at a location between the door and the supported articles, upwardly to a level above the latter and providing the front wall of a water chamber surrounding the articles, said partition being movable to facilitate insertion and removal of the articles, a free-overflow formation at the upper edge of said partition, water inlet and outlet means for said water chamber, means to heat the water in the chamber so as to induce upward and forward currents therein, and collecting and discharging means for the fluid coming from the overflow formation.

18. Washer-sterilizer apparatus comprising in combination an autoclave having a charging door, a water chamber in the autoclave for immersing articles to be washed and sterilized, said chamber having at an upper level a horizontally extensive free-overflow formation, means to heat the water sufficiently to evolve steam under pressure in the autoclave and to cause the water with surface-carried matter from the articles to overflow the said formation, collecting and discharging means for said overflowing fluid, and a flash tank communicating with the water chamber and into which the residual heated water under pressure may be released from said chamber to atmospheric pressure.

19. In a sterilizer apparatus having a compartment in which water is adapted to be heated under pressure of steam therefrom and at temperatures above that of normal atmospheric boiling, a valve-controlled drain conduit in communication with said compartment through a lower wall portion thereof, a closed tank into which said conduit opens, the tank having a vent for vapor forming therein, and a sealed trap drain leading out from near the bottom of the tank to carry off the residual water, the tank being shaped and arranged relative to the water inlet to deflect and distribute the incoming stream of water throughout the tank.

20. The method of washing and sterilizing contaminated articles which comprises confining a body of water together with an overlying enclosed space, immersing the articles in the water so confined, heating the water to a steam-evolving state and causing it to overflow from said body expansively at its surface level while simultaneously causing the contaminating matter on the articles to be carried to the surface of the water and there to spread and pass off with the overflow until but substantially a monomolecular film remains at the water surface, discharging the overflow, continuing the heating action to produce a positive sterilizing temperature, determining the arrival of said condition and discontinuing the heating action, and draining off the water and relieving the associated steam pressure, thereby presenting the articles in sterile condition for use.

21. Washer-sterilizer apparatus including in combination with a pressure-tight main shell, a chamber therein to contain water of a depth and volume adequate for immersing articles to be washed and sterilized, a steam coil at the lower

portion of the water chamber and arranged so to concentrate the heat as to induce upward and returning convection currents in the water, baffle means adjacent the steam coil to assist in directing said currents, foraminous supporting means presenting the immersed articles in the path of said currents, a horizontally extensive upright knife-edge formation at an upper wall portion of the chamber and disposed for overflow flowing by the rising heated water, and pressure-retaining means for carrying off the overflow.

15 22. Washer-sterilizer apparatus comprising a pressure-tight enclosure having therein an article-receiving water chamber, means to heat the water under pressure of steam therefrom in said enclosure, means on a wall of the chamber at an upper portion thereof, said means defining the maximum water level and permitting water to overflow as it rises under the expanding action of the heat, a collecting reservoir for the overflowing water, and temperature-responsive means for discharging the water from the reservoir at a rate to avoid any blocking of the overflow from the chamber to the reservoir and while maintaining the temperature and pressure in the apparatus as a whole.

25 23. Washing and sterilizing apparatus for surgical instruments and other articles, comprising a sterilizer having therein a water chamber with an over-lying confinable space, heating means to supply heat to the water in said chamber for creating steam under greater than normal atmospheric pressure in the sterilizer, fluid discharging means for air, steam and water automatically effective to afford a definite steam-pressure and temperature relation in the sterilizer and to relieve air therefrom during creating and maintenance of said pressure and temperature relation, a cut-off device for the heating means adapted for actuation on arrival of a predetermined pressure-temperature condition in the sterilizer, a common inlet and drain port for the water, and valve means communicating with said port and with water supply and water drain conduits respectively, said valve means adapted selectively for admitting water to the chamber, for complete closure during a washing and sterilizing operation, and for draining the water from the chamber.

30 24. Washing and sterilizing apparatus for surgical instruments and other articles, comprising a sterilizer having therein a water chamber with an overlying confined space, means to supply heat to the water for creating steam under greater than normal atmospheric pressure in the sterilizer, fluid discharging means for air, steam and water automatically effective to afford a definite steam-pressure and temperature relation in the sterilizer and to relieve air therefrom during creating and maintenance of said pressure and temperature relation, gage means to indicate arrival of a selected temperature as measured in terms of said definite steam-pressure condition in the sterilizer, and means to cut off said heat supply following such indication.

35 25. Washing and sterilizing apparatus for surgical instruments and other articles, comprising a sterilizer having therein a water chamber with an overlying confined space, means to supply heat to the water for creating steam under pressure in the sterilizer, said chamber having at an upper portion a horizontally disposed overflow formation defining the upper level of the water and the lower level of the space above the water, said formation providing for the escape of ris-

ing heated water substantially solely at the surface level thereof, a thermally responsive device subject to temperature conditions of the sterilizer, and means controlled by said device automatically to effect the cutting off of the heat supply at a predetermined temperature in the steam-pressure-subject heated interior of the sterilizer.

26. Washing and sterilizing apparatus comprising in combination a sterilizer having in it a closeable water chamber in which articles may be immersed, heating means for water in said chamber to create in the sterilizer steam under greater than normal atmospheric pressure and a temperature above the normal atmospheric boiling point of water, and fluid overflow and discharge means constructed and arranged to provide for an overflowing escape of the water substantially solely at its surface level while maintaining the temperature and pressure in the sterilizer, thereby to carry off from the latter contaminating matter rising from the articles to the surface of the water.

27. Washing and sterilizing apparatus comprising in combination a sterilizer including a closure-equipped chamber providing for the reception of a body of water and for a confined space above the upper water level, said water body of a volume to submerge a load to be sterilized, a water-confining wall in the chamber having a horizontal upper terminal portion 30

spaced below the top wall of said chamber, to define the water level and to permit overflowing passage thereof substantially solely at the surface level of the water, means to heat the water in said chamber to temperatures above that of the normal atmospheric boiling point, and heat-supply control means adapted for shutting off the heat supply on the arrival of a definite predetermined pressure-temperature condition in the sterilizer.

28. Washing and sterilizing apparatus comprising a sterilizer having therein a water chamber with an overlying confinable space and having provision for admitting water to and subsequently draining water from said chamber, heating means for water in said chamber to create steam under pressure in the sterilizer, fluid discharging means effective to relieve air from and to afford a definite steam-pressure-and-temperature relation in the sterilizer, and control mechanism for the heating means adapted for shutting off the latter at a determined pressure-temperature condition in the sterilizer, said fluid discharging means including an overflow formation providing for escape of water substantially solely at its surface level during the building up and maintenance of the determined pressure-temperature condition.

CARL W. WALTER.
